STOCK FEEDING AND GRIPPING DEVICE

Max E. Lange, Cleveland Heights, and William J. Burger, Shaker Heights, Ohio, assignors to The Warner & Swasey Company, Cleveland, Ohio, a corporation of Ohio

Application July 17, 1934, Serial No. 735,704

20 Claims. (Cl. 29—59)

This invention relates to a stock feeding and gripping device adapted to be used upon various types of machine tools wherein the stock is intermittently fed longitudinally to form work pieces of predetermined length, as for example a turret lathe and the like.

An object of the invention is to provide a stock feeding and gripping device which can be used with a feed tube for feeding stock of smaller diameters or can be used without a feed tube and with a movable stock feeding head for feeding stock of larger diameters.

Another object is to provide a stock feeding and gripping device which includes means for readily varying the length of the feeding movement and, therefore, the length of the work pieces.

Another object is to provide a stock feeding and gripping device which includes adjustable means that accurately determines the length of the feeding movement and the length of the work pieces.

Another object is to provide a stock feeding and gripping device which is operated by means of levers and wherein the movement of one lever in one direction releases the grip of the collet on the stock and feeds the stock a predetermined distance, the movement of the same lever in the reverse direction restoring the grip of the collet upon the stock, while movement of another lever acts to restore the stock feeding member to its initial position.

Another object is to provide a stock feeding and gripping device that is efficient in operation and control.

Another object is to provide a stock feeding and gripping device which is simple in construction and direct, positive, flexible and accurate in its operation.

Further and additional objects and advantages will become apparent hereinafter during the detailed description which follows of several embodiments of the invention, as illustrated in the accompanying drawings, wherein

Fig. 1 is a side elevational view showing a machine employing one embodiment of the present invention and utilizing a feed tube for feeding the stock;

Fig. 2 is a top plan view of the machine and stock feeding and gripping device shown in Fig. 1;

Fig. 3 is an enlarged fragmentary plan view of the stock feeding device shown in Fig. 2, the operating levers of the device being shown in one position in full lines and in another position in dotted lines, while certain portions of the machine

have been omitted to clearly illustrate the spindle;

Fig. 4 is a front elevation of Fig. 3 with the operating levers and connected parts positioned in the full line showing of Fig. 3;

Fig. 5 is a view similar to Fig. 4, except that the operating levers and connected parts are positioned in the dotted line showing of Fig. 3;

Fig. 6 is a side elevational view of a machine employing a different embodiment of the invention from that shown in Figs. 1 to 5, inclusive, and one wherein the stock feeding and gripping device acts to feed the stock by means of a movable stock feeding head in place of the feed tube disclosed in the first mentioned form.

Fig. 7 is a top plan view of the machine and stock feeding and gripping device shown in Fig. 6, with the stock housing tube detached from the stock feeding and gripping device and moved to stock loading position;

Fig. 8 is an enlarged fragmentary elevational view of a portion of Fig. 6, with certain parts of the machine omitted to clearly show the spindle and with certain parts of the stock feeding and gripping device shown in section, it being noted that the movable stock feeding head is differently positioned than in Fig. 6;

Fig. 9 is a view similar to Fig. 8 with the operating lever and its connected parts shown in a different position;

Fig. 10 is a side elevational view of a machine employing a still different embodiment of the invention from those previously illustrated and one wherein the device may be used with a stock feeding tube or with a movable stock feeding head;

Fig. 11 is a top plan view of Fig. 10 with the stock housing tube shown in stock loading position;

Fig. 12 is an enlarged fragmentary elevational view of a portion of Fig. 10, certain parts of the machine having been omitted to clearly illustrate the spindle and the stock feeding and gripping device being shown as operating with a stock feeding tube;

Fig. 13 is a view similar to Fig. 12 with the operating levers of the stock feeding and gripping device and their associated parts shown in a different position than in Fig. 12; and

Figs. 14 and 15 are views similar to Figs. 12 and 13, respectively, except that the stock feeding and gripping device is not employed with a stock feeding tube but is employed with a movable stock feeding head.

Referring first to the embodiment of the in-

vention shown in Figs. 1 to 5, inclusive, and particularly to Figs. 1 and 2, there is partially shown a turrent lathe comprising a bed 20 and a head 21 extending through which is a rotatable spindle 22. The spindle 22 houses an endwise movable collet operating sleeve 23, see Fig. 3, which when moved in one direction moves a spring-jawed collet 24 into gripping relation with the stock, as is well understood, and when moved in the opposite direction allows said collet to release its grip upon the stock. The collet actuating sleeve 23 is moved to cause the collet to grip the stock by means of pivoted fingers 25 having heel portions which engage the ends of the sleeve and being provided with rollers bearing upon a sliding wedge-operating cone 26 mounted on the spindle 22. A slidable stock feeding tube 27 extends into the collet actuating sleeve 23 and is provided at its inner end with the usual stock gripping fingers. The parts thus far described are conventional and do not constitute any part of the present invention, except in so far as they cooperate with the various elements of the stock feeding and gripping device which are operatively associated with the cone 26 and the feed tube 27.

A rod 28 extends from the rear end of the head and is supported by the stock stands, later to be referred to, and also by a bracket 29 secured to the rear end of the head. The bracket 29 adjacent the rear end of the head carries a vertically extending lever support upon which is pivotally arranged an operating lever 30 for restoring the feed tube to initial position and an operating lever 31 for actuating the cone 26 and for actuating the feed tube in a stock feeding direction. The lever 30, as will later be explained, has a direct connection with the feed tube for restoring the same to its initial position and the lever 31 has a direct connection with the cone 26 and an operative connection with the feed tube for moving the latter in a stock feeding direction. The lever 30 is provided with an extension beyond the lever support and toward the back of the machine, see Fig. 3, which is pivotally connected at its end to a connecting rod 32, which in turn is pivotally connected to a slide 33 mounted upon the rod 28. The slide 33 is provided with an upwardly extending shoe engaging between flanges formed on the rear end of the feed tube 27, whereby movement of the slide 33 similarly moves the feed tube 27. The lever 31 is provided with a lug 34 to which is pivotally connected a link 35 in turn pivotally connected to a slide 36 on the rod 28, said slide having an upwardly extending fork carrying rollers engaging in a groove in the wedge cone 26. It will thus be seen that movement of the lever 31 effects a direct and positive movement of the cone 26. The lever 31 forwardly of the lug 34 is provided with a second lug 37 which rotatably supports a pin 38 having on the upper side of the lug an enlarged portion 39 through an opening in which a rod 40 slidably extends, said rod being pivotally connected to the slide 33 and carrying on the opposite side of the pin 38 from the slide 33 an adjustable stop 41. It will be seen that when the lever 31 is moved from the full line position of Fig. 3 to the dotted line position thereof, it will first move the cone 26 to release the collet 24 from stock gripping position, after which the enlarged portion 39 of the pin 38 carried by said lever will engage the stop 41 on the rod 40 and cause a movement of the slide 33 and a movement

of the feed tube 27 to feed the stock through the collet.

The movement of the lever 31 from the full line position of Fig. 3 to the dotted line position thereof acts to move the lever 30 from the full line position to the dotted line position, since the lever 30 is connected to the slide 33. When the lever 31 is in the position shown in full lines in Fig. 3, the parts of the device are in the position illustrated in Fig. 4, while when the lever 31 is in the position shown in dotted lines in Fig. 3, the parts are in the position illustrated in Fig. 5. After the lever 31 has been moved, as just described, to release the gripping of the collet and to feed the stock through the collet, this lever is then moved in the reverse direction to cause the collet, through the intermediary of the sleeve 23 and cone 26, to grip the stock, it being noted that the reverse movement of the lever 31 does not effect any movement of the slide 33, since the enlarged portion 39 of the pin 38 carried by the lever moves away from the stop 41 on the rod 40 and does not move the rod. The stock having been gripped by the collet, the lever 30 is now moved away from the dotted line position shown in Fig. 3, to the full line position shown in said figure, whereupon the slide 33 is moved rearwardly or to the left, as viewed in the drawings by the rod 32 and the feed tube restored to its initial position, it being understood that the gripping fingers in the inner end of the feed tube slide over the stock during the movement of the tube.

It will be noted that the stop 41 is adjustable on the rod 40 and that the position of said stop determines the length of travel of the feed tube 27 effected by the movement of the lever 31 and as a result the length of feed of the stock. In this connection it will be noted that the maximum movement of the lever 31 from left to right, as viewed in the drawings, is determined by the abutting engagement of the forward end of the slide 36 with the boss 29a of the bracket 29, as shown in Fig. 5. This engagement of the slide 36 with the boss 29a also determines the maximum length of travel of the slide 33 and the feed tube 27, and consequently the maximum length of feed of the stock. It will be noted that the lever 31 must move at all times sufficiently far before the pin 38 carried thereby engages the stop 41 to effect a movement of the cone 26, such that the collet will release its grip on the stock.

As is customary, means is provided for supporting and housing the stock extending from the rear end of the feed tube, said means including a pair of stock stands 42 interconnected by the rod 28 to form a unitary structure. The rear stock stand 42, that is the left-hand stand as viewed in Figs. 1 and 2, is provided at its upper end with a swivelly mounted sleeve 43 through which extends and is rigidly connected thereto the stock housing tube 44. The other stock stand 42 is provided at its upper end with a supporting portion 45 for the tube 44, which portion has a laterally extending arm 46 for supporting the housing tube 44 when the latter is swung outwardly to loading position, as indicated in dotted lines in Fig. 2. The supporting portion 45 is also provided with a clamping latch 47 for holding the tube 44 in axial alignment with the feed tube 27. The forward or right-hand end, as viewed in the drawings, of the housing tube 44 is provided with suitable means for clamping the stock during the loading opera-

tion. In the present instance this means is a vise 48 consisting of opposed jaws slidably supported by means of a dovetail connection with the body of the vise and movable toward and away from the stock by means of a right and left-hand screw. When it is necessary to insert a new bar of stock into the feed tube the stock housing tube 44 is moved to the dotted line position of Fig. 2, the bar of stock inserted therein and said tube then moved into alignment with the feed tube and locked in such position. The feed tube 27 is then moved to its innermost position, as shown in Fig. 5, after which the bar of stock is pushed inwardly of the feed tube until its inner end abuts with the spring fingers on the end of the feed tube; then the jaws of the vise 48 are brought into holding engagement with the bar of stock, after which the feed tube is moved rearwardly into the position shown in Fig. 3, which movement causes the spring fingers on the end of the feed tube to open and ride upon the bar of stock and then be in gripping position thereon. After the stock has been gripped by the fingers of the feed tube the vise 48 is released and does not function again until a new bar is inserted.

The operation of the stock feeding and gripping device, comprising the embodiment heretofore described, is as follows:

Assuming that a stock bar has been inserted, as heretofore explained, and that a work piece has been completed and severed from the bar and also that the stop 41 has been properly adjusted to enable the device to feed the desired length of stock, the lever 31 is moved from the full line position of Fig. 3, to the dotted line position thereof. This movement of the lever 31 first moves the wedge cone 26 to allow the collet 24 to release its grip on the stock and then effects an engagement of the enlarged portion 39 of the pin 38 with the stop 41 to cause a movement of the rod 40 and slide 33 until the slide 36 abuts the boss 29a, resulting in a feeding movement of the feed tube 27 and the stock and in the movement of the lever 30 to the dotted line position of Fig. 3. The lever 31 is then moved in the reverse direction, that is, from the dotted line position of Fig. 3 to the full line position thereof, whereupon the wedge cone 26 moves from the position shown in Fig. 5 to that shown in Fig. 4 and the collet 24 is again caused to grip the stock, it being remembered that this last mentioned movement of the lever 31 does not effect any movement of the slide 33 and feed tube 27. After the collet 24 has again gripped the stock, the lever 30 is moved from the dotted line position of Fig. 3 to the full line position thereof and, since said lever is connected by the rod 32 with the slide 33 the latter and the feed tube 27 are moved from the position shown in Fig. 5 to that shown in Fig. 4, the feed tube fingers during such movement riding over the stock which is now gripped by the collet.

The embodiment of the invention illustrated in Figs. 6 to 9, inclusive, is of such character that the feed tube, as shown in the first embodiment, is omitted. The present embodiment is suitable for use upon machines operating on the larger diameter stock, that is, stock which is sufficiently large and rigid to prevent exposed and unsupported lengths thereof from whipping during rotation.

In the present embodiment those parts which operate the collet 24, namely, collet actuating sleeve 23, wedge cone 26, and pivoted fingers 25

are substantially the same as in the previously described form. The wedge cone 26 is actuated by a lever 49 pivotally mounted on the head 21 of the machine and connected by a link 50 to a lever 51 pivoted intermediate its ends on a bracket 52 secured to the end of the head, said lever 51 at its upper end being provided with a fork straddling the cone 26 and having rollers engaging in the annular groove in said cone. It will be noted that movement of the lever 49 from the position shown in Fig. 8 to that shown in Fig. 9 effects a movement of the cone 26 such that the collet 24 releases its grip on the stock. As in the previously described form a rod 53 is secured to the bracket 52 and extends through one of the stock stands 54 and is secured to the other of the stock stands 54, thus interconnecting the same.

The rod 53 between the bracket 52 and the stock stand 54, through which the rod extends, is provided on its upper side with an elongated slot 55 slidably arranged in which is a ratchet bar 56. The ratchet bar 56 on a portion thereof adjacent the head of the machine is not provided with ratchet teeth, said portion being recessed for a part of its length forming stop shoulders 56a and 56b, see Figs. 8 and 9. A slide 57 is arranged on the rod 53 and embraces that portion of the ratchet bar between the stop shoulders 56a and 56b. The slide 57 is provided with an upwardly extending shoe engaging in the groove of the wedge cone 26, wherefore it will be seen that when said wedge cone moves movement will be imparted to the slide 57.

A second slide 58 is arranged on the rod 53 and embraces that portion of the ratchet bar that is provided with ratchet teeth. The slide 58 has a downwardly extending forked portion 59 which straddles a rod 60 secured to the bracket 52 on the head of the machine and to the inner of the stock stands 54, thus providing means for maintaining the slide 58 in an upright position. The slide 58 is provided with an upwardly extending portion 61 forming a head in which is rotatably secured a vise 62 in the present instance provided with a plurality of radially extending clamping screws 63 for gripping the stock, as will later be explained. The slide 58 above the rod 53 is provided with a pawl 64 cooperating with the ratchet teeth of the ratchet bar 56 and counterweighted by a handle 64a. The slide 58 is provided with a second upwardly extending portion 65 having a bore into which extends the end of a stock housing tube 66. The stock housing tube 66 adjacent the end thereof that extends into the bore of the slide 58 is provided with an annular flange 67 abutting against the portion 65. The portion 65 of the slide 58 is provided with an arm 68 of such length as to extend over and beyond the flange 67 of the housing tube 66, it being noted that the arm 68 on its inner side is provided with a groove, see Figs. 7 and 9. The portion 65 of the slide 58 is further provided with a rearwardly extending boss upon which is pivotally mounted a latch lever 69 which when the end of the tube 66 is arranged in the bore of the portion 65 may be swung into the groove on the underside of the arm 68 and thus will engage the flange 67 on the opposite side thereof from the portion 65 to hold the end of the tube in the bore of the portion 65 and thus connects the housing tube 66 to the slide 58.

The housing tube 66 is slidably supported adjacent its rear end by a sleeve 70 swivelly mounted on the upper end of the rear stock stand 54, so that the housing tube 66 may be swung to the

position shown in Fig. 7 to enable a length of stock to be inserted into the tube. When the stock has been inserted into the tube 66 the tube is shifted a distance to the rear and then swung 5 into alignment with the bore in the portion 65 of the slide 58. The stock is then pushed through the portion 65 and the vise 62 of the slide 58 and into the spindle 22 until a certain length of the stock projects beyond the collet 24. Then the 10 tube is moved endwise until its end has entered the bore of the portion 65 and the flange 67 is in engagement with said portion, whereupon the latch lever 69 is swung into the groove in the arm 68 and behind the flange 67, whereby the slide 15 68 and the tube 66 are interconnected. The clamping screws 63 of the vise 62 are then brought into clamping engagement with the stock, so that as the slide 58 moves the stock will move. Assuming the stock to have been inserted into the 20 machine, as just referred to, and the parts to be in the position shown in Fig. 8, and that the work upon the length of stock projecting from the collet has been completed and the work blank 25 severed therefrom, movement of the lever 49 to the right, as viewed in the drawings and from the position shown in Fig. 8 to that shown in Fig. 9, effects the following result:

The initial portion of the movement of the lever 49 serves to withdraw the wedge cone 26 from 30 between the ends of the pivoted fingers 25 and to release the grip of the collet 24 upon the stock. During this initial portion of the movement of the lever 49 and the movement of the wedge cone 26, the slide 57, operatively connected with said cone, moves so that its rear end disengages the stop shoulder 56a of the ratchet bar 56, while its forward end comes into engagement with the stop shoulder 56b of said bar. The remainder of the movement of the lever 49, while continuing to 35 move the wedge cone 26, also effects, through the slide 57 which is now in engagement with the stop shoulder 56b, a movement of the ratchet bar 56 until the forward end of the ratchet bar abuts the boss on the bracket 52 which carries the rod 53, whereupon further movement of the lever 49 40 and of the slide 57 is arrested. After the lever 49 has been moved sufficiently to effect a release of the collet, as just explained, and to bring the slide 57 into engagement with the stop shoulder 56b, the further movement of the lever 49 moves the ratchet bar 56 toward the right, as viewed in the drawings, and since the counter-weighted pawl 44 carried by the slide 58 is in engagement with the ratchet teeth of the bar 56, the slide 58 will 45 move a corresponding distance to the right, that is, from the position shown in Fig. 8 to that shown in Fig. 9. This movement of the slide 58 causes a corresponding movement to be imparted to the stock which is gripped by the vise 62 carried by the slide, and also a corresponding movement to the stock housing tube 66 which is interconnected to the portion 65 of the slide 58. At the completion of the movement of the lever 49 to the right the stock will have been fed forwardly through 50 the collet the desired distance, whereupon the lever 49 is swung in the opposite direction to move the wedge cone 26 between the pivoted fingers 25 and to effect a gripping action of the collet upon the stock.

70 During this last named movement of the cone 26 the forward end of the slide 57 moves out of engagement with the stop shoulder 56b of the ratchet bar 56. While the rear end of the slide 57 engages the stop shoulder 56a whereupon the ratchet bar 56 is moved rearwardly or to the left,

as viewed in the drawings, the slide 58 remains stationary, since the pawl 44 rides over the teeth of the ratchet bar. Since the slide 58 moves forwardly during the feeding operation, but remains stationary while the ratchet bar is restored to its initial position, it will be seen that after a number of feeding operations the slide 58 will have been moved to its maximum forward position, such as shown in Fig. 6, that is, to a position closely adjacent to the spindle end. It will then be necessary to loosen the clamp screws 63 of the vise 62 and move the slide 58 and the stock housing tube 66 back to the position shown in Fig. 8, whereupon the screws 63 are again tightened and the operation of the machine continued. It will be understood that the maximum length to which the stock may be fed is determined by the engagement of the end of the ratchet bar 56 with the boss on the bracket 52, as previously explained. In the present embodiment of the invention it is proposed to employ a stock stop (not shown) on the turret or other part of the machine when it is desired to impart a feed to the stock less than the maximum feed.

A third embodiment of the invention is illustrated in Figs. 10 to 15, inclusive, and which is of such character that the stock feeding and gripping device may be adapted to function with a feed tube as in the first embodiment, or without a feed tube and with a movable stock gripping head, as in the second or last described embodiment.

In the embodiment shown in Figs. 10 to 15, inclusive, the spindle 22, collet actuating sleeve 23, collet 24, wedge cone 26 and pivoted fingers 25 are the same as the corresponding parts in the previously described embodiments and, therefore, are similarly numbered in this last embodiment.

A lever 71 is fixed to the outer end of a rod 72 (see Fig. 11) extending into and rotatably carried by the head 21 of the machine. The rod 72, 40 inwardly of the head, has secured thereto an arm 73 to which is pivotally connected a link 74 that projects through an opening in the end of the head and is pivotally connected to the end of a lever 75 in turn pivotally mounted intermediate 45 its ends upon a bracket 76 secured to the end of the head. The upper end of the lever 75 is provided with a forked portion having rollers engaging in the groove in the wedge cone 26, wherefore it will be seen that movement of the lever 71 will effect a sliding movement of the wedge cone 26 upon the spindle 22.

A slide 77 similar to the slide 57 is mounted on a rod 78 secured to the bracket 76 and extending through one of the stock stands 79 and secured to the other of said stands, which rod is similar to the rod 53 in the last described embodiment. The slide 77 carries an upwardly extending shoe engaging in the groove in the cone wedge 26, wherefore movement of the cone wedge, effected through movement of the lever 71, also acts to move the slide 77. The rod 78 is provided with an elongated longitudinally extending slot in which is slidably mounted a ratchet bar 80 provided with a portion having ratchet teeth and another portion without ratchet teeth. This latter portion of the ratchet bar is in turn provided with a recess somewhat longer than the length of the slide 77 and forming shoulders 80a and 80b at its opposite ends (see Figs. 12 and 13). It will be seen that movement of the slide 77 will cause its opposite ends to engage the shoulders 80a and 80b, respectively, whereupon the ratchet bar 80 will move with said slide.

As in the second embodiment, the rod 80 also

slidably supports a second slide 81 from the underside of which extends a forked portion 82 straddling a rod 83 secured to the stock stand 79 and to the bracket 76, whereby the slide 81 is maintained in upright position. The slide 81 is provided with an upwardly extending head 84 having a bore in which is rotatably secured a vise 85, for the same purpose as the device 62 in the second described embodiment and having oppositely movable jaws, such as are used in the vise 48 of the first embodiment.

5 a link 93, the opposite end of which is pivotally connected to a lever 94 pivotally mounted intermediate its ends upon a bracket 95 secured to the rod 83. The upper end of the lever 94 has a forked portion carrying rollers which engage between flanges on the end of the feed tube 96, wherefore it will be seen that oscillating movement of the operating handle 92 effects a reciprocating movement of the feed tube 96.

10 The slide 81, as in the second embodiment, is provided with a pawl having a counterweight in the form of a handle 86 for the same purpose as the pawl 64 in the second embodiment. The slide 81 is also provided with an upwardly extending portion spaced from the head 84 and having at its upper end an extended portion forming a support 87 for the end of the stock housing tube 88, it being noted that the flange on the end of said tube extends over the edge of the supporting portion 87. The stock housing tube 88 is in alignment with the bore in the head 84 and with the spindle 22 by means of a locking 15 latch 89 pivotally mounted upon the portion 87. It will be understood that when the latch 89 is lifted the stock housing tube 88 may be swung outwardly to the position shown in Fig. 11 for the purpose of loading stock in said tube, it being noted that the rearmost stock stand 79 carries at its upper end a swivelly mounted sleeve 90, through which the stock housing tube 88 slidably extends. It will be understood that the parts of this last embodiment of the invention 20 as thus far described will operate in the same manner as does the second embodiment of the invention; that is, assuming the stock to have been loaded into the spindle and to be gripped by the collet 24, movement of the lever 71 will effect the release of the gripping of the collet, the feeding movement of the stock, and the re-gripping by the collet.

25 The slide 81, as in the second embodiment, is provided with a pawl having a counterweight in the form of a handle 86 for the same purpose as the pawl 64 in the second embodiment. The slide 81 is also provided with an upwardly extending portion spaced from the head 84 and having at its upper end an extended portion forming a support 87 for the end of the stock housing tube 88, it being noted that the flange on the end of said tube extends over the edge of the supporting portion 87. The stock housing tube 88 is in alignment with the bore in the head 84 and with the spindle 22 by means of a locking 30 latch 89 pivotally mounted upon the portion 87. It will be understood that when the latch 89 is lifted the stock housing tube 88 may be swung outwardly to the position shown in Fig. 11 for the purpose of loading stock in said tube, it being noted that the rearmost stock stand 79 carries at its upper end a swivelly mounted sleeve 90, through which the stock housing tube 88 slidably extends. It will be understood that the parts of this last embodiment of the invention 35 as thus far described will operate in the same manner as does the second embodiment of the invention; that is, assuming the stock to have been loaded into the spindle and to be gripped by the collet 24, movement of the lever 71 will effect the release of the gripping of the collet, the feeding movement of the stock, and the re-gripping by the collet.

40 An adjustable stop 101 is mounted on the rod 99 between the levers 75 and 94 and is for a purpose similar to the purpose of the stop 41 in the first embodiment. When the present embodiment is employed without a feed tube, as illustrated in Figs. 14 and 15, the stop 101 is moved to an inoperative position, such as shown in Figs. 14 and 15, wherefore movement of the lever 71 effects no movement of the operating handle 92 and the lever 94.

45 However, when the present embodiment is used with a feed tube, as illustrated in Figs. 10 to 13, inclusive, the stop 101 is set in an operative position, that is, in such position that it will engage with the enlarged portion 100 of the shoulder pin carried by the lever 94 after the lever 71 has been swung to the right, as viewed in the drawings, sufficiently far to move the wedge cone 26 to collet releasing position. When the device is employed with a feed tube it will, 45 of course, be necessary to render the pawl carried by the slide 81 inoperative. This is accomplished by swinging the pawl handle 86 from the position shown in Figs. 14 and 15 to the position shown in Fig. 10 and locking the same in the latter position by means of a screw 102 which engages beneath a cutaway portion formed on the pawl handle.

50 When small diameter stock is being used with the feed tube, the slide 81 with the housing tube 55 88 secured thereto may be moved to and remain in a position adjacent the end of the feed tube, wherefore there will be no substantial length of stock not supported by and housed in either the feed tube or the housing tube 88, thereby eliminating likelihood of the stock whipping during the rotation of the stock when the machine is operating.

55 It will, of course, be understood that when the device is used with a feed tube the jaws of the vise 85 are moved out of gripping engagement with the stock, but are used during the loading of new bars of stock in the same way as are the jaws of the vise 48 in the first embodiment.

60 When it is desired to switch to the use of a feed tube, assuming the machine to have been operating without such tube, the bearing pin 103 for the lever 94 is withdrawn and said lever allowed to drop downwardly, whereupon the feed tube 96 may be inserted into the spindle, follow- 65 70 75

ing which the lever 94 is again moved upwardly and the rollers at the forked upper end positioned between the flanges on the end of the feed tube and the pin 103 is reinserted. Of course, to re-
5 move the feed tube the reverse operations are necessary.

The operation of the device just described and with the feed tube will now be explained with reference to Figs. 12 and 13. Assuming that a bar 10 of stock is in the spindle and that a work piece has just been completed and severed therefrom and that the stop collar 98 and the stop 101 have been properly adjusted for the length of feed desired, the lever 71 and its associated parts are 10 moved from the position shown in Fig. 12 to the position shown in Fig. 13. The initial portion of this movement of the lever 71 moves the wedge cone 26 to effect a release of the gripping action of the collet upon the stock. At the end of this 15 initial portion of the movement of the lever 71, the stop 101 comes into engagement with the enlarged portion 100 of the headed pin carried by the lever 94 and, therefore, the further movement of the lever 71 in the same direction effects 20 an additional movement of the cone 26 toward the right, as viewed in the drawings, and also a swinging movement of the lever 94 which in turn moves the feed tube inwardly of the spindle in a stock feeding direction to position a predetermined length thereof beyond the collet, until the 25 abutting portion 94b on the lever 94 engages the stop collar 97 thus preventing further movement of the lever. It will be understood that as the cone wedge 26 moves the slide 77 and the ratchet bar 80 also move, it being remembered that the pawl on the slide 81 is locked in an inoperative position and hence no movement is imparted to this latter slide. In order to again have the collet grip the work, the lever 71 must be moved 30 from the position shown in Fig. 13 to the position shown in Fig. 12. This movement of the lever moves the wedge cone 26 between the pivoted fingers 25 and causes the collet to grip the stock. However, it will be noted that said movement of the lever 71 in the last named direction does not 35 impart any movement to the lever 94, since the stop 101 merely moves with the rod 99 away from the enlarged portion 100 of the headed pin carried by the lever 94. After the collet has been 40 restored to gripping position, the operating handle 82 is moved from the position shown in Fig. 13 to the position shown in Fig. 12, with the result that the lever 94 is swung about its pivot until the abutting portion 94a engages the stop collar 45 98 and the feed tube moved rearwardly to its former position, it being understood that the spring fingers at the end of the tube slide over the surface of the stock. This last named movement of the lever 94 returns the enlarged portion 50 100 of the headed pin to a position shown in Fig. 12, wherein the stop 101 is separated therefrom a proper distance to permit the cone wedge 26 to first be moved to collet releasing position upon movement of the lever 71 before the stop 55 engages with the portion 100.

Having thus described our invention, we claim:

1. In a stock feeding and gripping device for a machine tool, stock gripping means, stock feeding means, and manually movable means for 60 effecting release of the gripping means, actuation of the feeding means and closing of the gripping means, and a second manually movable means for restoring said feeding means to its initial position and independently of the movement of said first named manually movable means.

2. In a stock feeding and gripping device for a machine tool, a stock gripping collet, a slid-
5 able stock feeding tube, and manually movable means operable in one direction for releasing the collet and positively moving the feed tube to feed the stock.

3. In a stock feeding and gripping device for a machine tool, a stock gripping collet, a slid-
10 able stock feeding tube, and manually movable means operable in one direction for releasing the collet and positively moving the feed tube to feed the stock and operable in the opposite direction to close the collet.

4. In a stock feeding and gripping device for a machine tool, a stock gripping collet, a slid-
15 able stock feeding tube, manually movable means for effecting release of the collet, movement of the tube to feed the stock and then closing of the collet, and a second manually movable means for imparting movement to said tube to 20 restore the same to its initial position independently of the movement of said first named manually movable means.

5. In a stock feeding and gripping device for a machine tool, a stock gripping collet, a stock feed-
25 ing tube, means for actuating said collet, means for actuating said stock feeding tube, and manu-
ally movable means having a positive operative connection with said collet actuating means and a lost motion operative connection with the ac-
30 tuating means for said stock feeding tube whereby movement of said manually movable means in one direction effects a release of the collet and then a positive feeding of the stock.

6. In a stock feeding and gripping device for a machine tool, a stock gripping collet, a stock feed-
35 ing tube, means for actuating said collet, means for actuating said stock feeding tube, a manually movable means having a positive operative connection with said collet actuating means, and 40 adjustable means affording a lost motion operative connection between said manually movable means and the means for actuating the stock feeding tube when said manually movable means is moved in one direction to positively move the 45 tube.

7. In a stock feeding and gripping device for a machine tool, a stock gripping collet, stock feed-
50 ing means, manually operable means having a positive operative connection with said collet for actuating the same, and adjustable means for connecting said manually operable means with said stock feeding means first with a lost motion connection and then with a positive operative connection to positively feed the stock.

8. In a stock feeding and gripping device for a machine tool, a stock gripping collet, a slid-
55 able stock feeding tube, manually movable means, and means for positively operatively connecting said manually movable means with said collet to actuate the latter and for operatively connecting said manually movable means with said feed tube with a lost motion connection to actuate the latter in a stock feeding direction, and a second manually movable means having a positive operating connection with said feed tube for restoring the same to its initial position after a stock feeding operation.

9. In a stock feeding and gripping device for a machine tool, a stock gripping collet, a slide op-
70 eratively associated with said collet for actuating the same, manually movable means positively connected with said slide, a feed tube, a second slide operatively associated with said tube, and means connecting said second slide with said 75

- manually movable means with a lost motion connection whereby movement of said manually movable means in one direction effects a feeding movement of said tube.
- 5 10. In a stock feeding and gripping device for a machine tool, a stock gripping collet, a slide operatively associated with said collet, manually movable means for moving said slide in opposite directions to open and close said collet, a feed tube 5 for feeding the stock, a second slide operatively associated with said feed tube, a rod connected with said second slide and having a slidable connection with said manually movable means, and an adjustable stop carried by said rod and adapted 10 to be engaged by a portion of said manually movable means during its movement in one direction to effect a movement of said second slide and a feeding movement of the tube.
- 10 11. In a stock feeding and gripping device for 20 a machine tool, a stock gripping collet, a slide operatively associated with said collet, manually movable means for moving said slide in opposite directions to effect an opening and closing of said collet, a feed tube for feeding the stock, a second slide operatively associated with said tube, means 25 providing a lost motion connection between said second slide and said manually movable means when the latter moves in one direction, a second manually movable means, and means positively connecting said second manually movable means with said second named slide.
- 15 12. In a stock feeding and gripping device for a machine tool, a stock gripping collet, means for opening and closing said collet, manually movable means having a positive operative connection with said last named means whereby its movement in opposite directions actuates said collet, a movable stock feeding head including a stock gripping vise, and means for operatively connecting 30 said head with said manually movable means during the movement of the latter in one direction and including a slide operatively connected with said collet actuating means, a movable ratchet bar having a lost motion connection with 35 said slide, and a rockable pawl carried by said head and operatively engaging the teeth of said ratchet bar when the bar moves in one direction.
- 20 13. In a stock feeding and gripping device for a machine tool, in combination, a stock gripping collet, means for opening and closing said collet, manually movable means for actuating said first means, a slidable stock housing tube, a movable stock feeding head including a stock gripping vise, and means for locking said head to said 40 housing tube, means for operatively connecting said housing tube and said head to said manually movable means when the latter moves in a direction to effect release of the collet, said last means including a slide operatively connected with said collet actuating means, and a movable ratchet bar having a lost motion connection with said slide, and a rockable pawl carried by said head and operatively engaging the teeth of said ratchet bar when the latter moves in one direction.
- 25 14. In a stock feeding and gripping device for a machine tool, a stock gripping collet, means for actuating said collet including a movable wedge cone and a pivoted lever operatively associated with said cone, manually movable means having 45 an operative connection with said lever, a stock feeding tube, a pivoted lever operatively associated with said tube, a second manually movable means operatively connected with said second named lever, a rod connected with said first named lever and having a sliding connection with said second named lever, and an adjustable stop carried by said rod and adapted to be brought 50 into engagement with said second named lever when said first named lever moves in one direction whereby movement of said first named manually movable means in one direction effects an opening of the collet and then a feeding movement of the feed tube while its movement in the opposite direction effects a closing of the collet.
- 30 15. In a stock feeding and gripping device for a machine tool, a slidable stock housing tube, a movable stock feeding head including a stock gripping means, means for locking said head to said tube, and means for moving said head.
- 35 16. In a stock feeding and gripping device for a machine tool, a movable stock feeding head including a stock gripping means, a pivoted stock housing tube, means for locking said head to said tube when the latter is aligned therewith, and means for moving said head.
- 40 17. In a stock feeding and gripping device for a machine tool, a movable stock feeding head including a stock gripping means, a slidably and pivotally mounted stock housing tube, means for locking said head to said tube when the latter is aligned therewith, and means for moving said head.
- 45 18. In a stock feeding and gripping device for a machine tool, a movable stock feeding head including a stock gripping means, a pivoted stock housing tube adapted to be aligned with said head or to be swung out of alignment therewith, a stationary support for said tube when the latter is swung out of alignment with said head, means for locking said head to said tube when the latter is aligned therewith, and means for moving said head.
- 50 19. In a stock feeding and gripping device for a machine tool, a movable stock feeding head including a stock gripping means, a pivoted stock housing tube adapted to be aligned with said head or to be swung out of alignment therewith, means carried by said head for supporting said tube when the latter is out of alignment with the head, means for locking said head to said tube when the latter is in alignment therewith, and means for moving said head.
- 55 20. In a stock feeding and gripping device for a machine tool, stock gripping means, stock feeding means, a pivoted stock housing tube provided at its end adjacent the said gripping means and said feeding means with means for clamping the stock whereby when said tube is aligned with said gripping means and said feeding means the stock may be held stationary by said clamping means until the stock feeding means has been properly positioned for the feeding of the stock after which the clamping means is released and the stock is moved forward by the feeding means and into the gripping means.
